Si, oggi a questo punto, uno dei maggiori problemi della
politica europea è rappresentato da un certo numero di
paesi che intendono uscire dalla legge comune di mercato
e dalla legge di base europea così come sono
attualmente applicate, si può dire, in gran parte dei paesi
europei, e se si considera che la legge comune di mercato
è stata approvata da tutti i paesi europei, e che la legge
di base europea è stata approvata da tutti i paesi europei,
allora, non è possibile che questi paesi possano uscire
dalla legge comune di mercato e dalla legge di base
europea senza che ciò possa essere considerato un
attacco alla legge comune di mercato e alla legge di base
europea.

UNITED STATES PATENT OFFICE

2.516.171

THREADING DEVICE

Solomon Adler, Kew Gardens, N. Y.

Application August 30, 1946, Serial No. 693,919

15 Claims. (Cl. 112—225)

This invention relates to a threading device and, more particularly, to a device for guiding a thread through the various eyelets and apertured guides of a sewing or similar machine.

The number of these thread guides in the conventional type of sewing machine is comparatively large. Many machines have nine and more thread guides. The problem to pass the thread through all these openings takes up a considerable amount of the operator's time and energy. In addition, if only one of the guide holes is inadvertently skipped the thread will inevitably break. Furthermore, the number and location of the guides varies in the several types of machines. This increases the difficulty of threading for an inexperienced worker and also for skilled workers who are not familiar with a particular make or type of machine.

It is an object of this invention to solve these problems by providing a device which performs the threading operation automatically, leaving to the hand only the final threading of the eye of the needle.

A further object is the formation of the threading device in a machine such that it can be operated without causing the stitching mechanism to function. A still further object is to provide for an automatic tripping of the device after the threading operation has been terminated.

These and other advantages will appear more fully from the following description of the machine which will be made with reference to the accompanying drawings illustrating one practical embodiment of the invention and in which:

Fig. 1 is a side elevation of the machine; Fig. 2 is a similar view, partly in section and

Fig. 2A is a detail view in a section on lines 2A—2A of Fig. 2 and illustrates the driving means for the spiral spring which constitutes the threader member of the machine;

Fig. 3 is a top plan view of the machine, without cover plates; Fig. 4 is a front view; and Fig. 5 is a

Fig. 4 is a somewhat diagrammatical, transverse sectional view on lines 4-4 of Fig. 3;

Fig. 5 is a transverse section on lines 5-5 of Fig. 2; 10μ thick and stained with

Fig. 6 is a circuit diagram illustrating the starter and circuit breaker switch of the device.

Referring primarily to Fig. 2 it will be seen that the machine is provided with a base and top portion and has a longitudinal drive shaft in each of these two portions. The upper drive shaft operates the needle bar 41 and thread take-up

39. The lower shaft serves the feed 11 and bobbin casing 18. The drive shafts are composed of inner members 1 and 2 and outer members 3 and 4 capable of being telescoped thereover. The latter ports have short stub shafts 5 and 6, connected by clutch devices 7 and 8 to their front ends. This arrangement is for the purpose of expanding and contracting the machine longitudinally. This mechanism will be referred to herein only briefly and the term "drive shaft," whenever used in this description or the appended claims, should be understood as including the composite whole of the telescoped members and short stub shafts. The expanding and contracting mechanism just referred to is the subject matter of a separate application for United States Letters Patent on "Sewing Machine" identified under Serial No. 693,914 and bearing the filing date August 30, 1946.

20 The machine receives its motive power from a small electric motor which is generally designated M. The motor drives the machine through a motor shaft and gear 9 and a transverse shaft 10, called herein "head shaft" (Figs. 3 and 4).
22 The head shaft forms a sliding fit in a bushing 11 which is provided with a bevel gear 12 and is in mesh with the motor gear 9 at all times. A slot and spline arrangement assures that the shaft 10 is rotated together with the bushing 11 without any relative rotation of the two parts.
24 The head shaft also carries two oppositely disposed bevel gears 13 and 14 at its front end. The lower drive shaft is likewise provided with two opposed bevel gears 15 and 16 and the corresponding upper drive shaft carries an end bushing 17 with a bevel gear 18, see Fig. 2. The operating connection between the upper and lower drive shaft is established by a vertical shaft 19 which has bevel gears 20 and 21 at its two ends.

40 Parallel to this vertical shaft which connects the drive shafts is another vertical shaft 22 which likewise has bevel gears at its two ends, these being numbered 23 and 24. The machine is also provided in its upper portion with a trans-
45 verse shaft 25 which, at its rear end, carries a bevel gear 26 and, at its front end, is provided with a worm gear 27. The worm gear is in engagement with a pinion gear 28 of a shaft ex-
tending lengthwise of the top portion of the ma-
50 chine. The latter shaft, herein designated the threading shaft, consists of two telescoped mem-
bers 29a and 29b, and is adapted like the drive shafts 1 and 2 to be expanded axially. Disposed at the forward end of the threading shaft is a
55 bevel gear 30. The shaft also has a circum-

ferential worm gear 31 located slightly to the rear of its front end. Provided on the frame are a sheave 32 and, associated therewith, a bevel gear 33. The latter gear is in engagement with the end gear 30 of the threading shaft.

The threading member proper is constituted by an endless spiral spring 34 which passes over the sheave 32 and, successively, through an eyelet 35, disposed on the tension device to be presently described, an eyelet 36, which forms part of the thread take-up 39, and two stationary eyelets 37 and 38.

A rod 40 is provided for the purpose of tensioning the spiral spring and thereby to take up the slack that may have developed through wear. Provision is thus made to assure at all times a good frictional engagement between the spiral spring and the aforementioned sheave 32. The tension rod 40 extends parallel to the needle bar 41, that is, at right angles to the threading shaft and is slidably fitted into an outer tube 42 carried by the frame. The tube is laterally slotted and thus provides the necessary clearance for an outwardly protruding cam member 43 attached to the lower portion of the tension rod. The cam member is connected by a pull cord 43a, which passes over a sheave 43b, to a securing block 44. The block is slideable on a rod 45 which extends parallel to the threading shaft. As appears from Fig. 1 the block has a protruding finger piece 46 which is accessible from the outside of the machine and adapted to move in a slot 47 of the cover plates of the machine. It also has a narrow plate-like lateral extension 48 directed parallel to the cover plate and in close abutment therewith. The extension plate is provided with a recess 49 which, when the block is slid to the right, registers with an inwardly projecting latch 50. An abutment 51 permits grasping of the finger piece 46 with the thumb while giving support to the middle finger.

The device is equipped with a switch S2 for starting the threading and a switch S3 for breaking the circuit at the completion of the operation. These two switches are in addition to the starter switch R of the stitching mechanism and switch S1 of the expansion and contraction mechanism. The latter switches will not be described herein, beyond indicating that their circuits are entirely separate from the circuit of the threading mechanism, as should be clear from an inspection of the diagram in Fig. 6.

The starter switch S2 of the threading mechanism is attached to the frame of the machine, see Figs. 3 and 4. Its lever 53 has a push-pull button 52 and, inwardly, a contact arm 54, bent back at right angles to the longitudinal axis of the lever. The contact arm is provided with a slanting abutment face 55 for engagement of a normally outwardly pressed switch knob 56. The switch, by virtue of this mechanism, is actuated when, by pulling out lever 53, knob 56 is pushed in. The switch is automatically opened as soon as the knob is released from the thrust of abutment 55.

The lever is also connected through a linkage 57, 58, 58a and 58b to a forked collar 59 disposed on the rearward end of the slide shaft 10. The linkage arrangement is of the reversing type so that by pulling the lever out, the shaft 10 is slid inwards. Therefore, when button 52 is pulled, switch S3 is closed, head shaft 10 is shifted and threading shaft 22 is engaged while gears 14 and 15 of the drive shafts are brought out of engagement.

The other switch of the device, switch S3, is normally closed. It is disposed at the underside of the top portion of the machine in close proximity to the forward end of the threading shaft. As is shown in Fig. 5, this switch is adapted slightly to oscillate in a horizontal plane on a stud 60. Its contact spring 60a is normally without reach but, by such oscillating movement, is brought within reach of abutment 61 of a rotating member 62, which is supported on a bracket 62a of the frame, and, at its top face, carries a pinion 63 as in Fig. 3. The pinion is disposed in mesh with the worm gear 31 of the threading shaft. In order to oscillate the switch as described, a prong 65 is swiveled on the frame. Its right hand fork is adapted to contact a projection 66 of the switch while the other prong is within reach of the cam 43. Therefore, when the cam is moved upwards, the swivel member is moved in a clockwise direction. Its right hand prong then imparts an oscillating movement to the switch, thereby moving its contact spring 60a into engagement position.

The operation of the device is as follows:

First, the slide block 44 is shifted to the right by means of the finger pieces 46 and 51 after unlocking of the latch 50. This raises the rod 40 and the eyelet 35 carried by it and, thereby, improves its frictional engagement by the driving sheave 32. Raising of the tension rod also moves the cam 43 upwards against action of the spring 74. The cam, by means of the intermediary swivel member 65, oscillates the switch S3 so that its contact spring 60a is moved slightly to the right. This brings the contact into engagement position with projection 61. After opening of the door 74 (Fig. 1) a spool of thread is placed on the swing arm 72 (Fig. 2) which is disposed close to the front end of the upper drive shaft. The thread is then passed over a tension device 13 of conventional design and is attached to the spiral spring 34 by placing it between any of the convolutions of the spiral at a place between the sheave 32 and the eyelet 35 of the tension rod.

The device is now ready for starting. Starting is effected by pulling out the knob 52. This closes the motor switch S3, and through linkage 57, 58, 58a, 58b and collar 59, moves the head shaft 10 so that the vertical shaft 22 of the threading mechanism is engaged and the stitching mechanism, composed of the shafts 1 and 2 and their vertical connecting shaft 19, is brought out of engagement.

The motor can now rotate the threading shaft through the head shaft and the connecting shafts 22, 25. The rotating movement of the threading shaft is transmitted through the bevels 30, 33 to the sheave 32 and thereby to the spiral 34 which passes the thread through the eyelets 35, 36, 37 and 38 in succession. The thread can then be taken from the spiral and be placed into slot 15 (Fig. 1) at the lower end of the needle bar to steady it for the threading into the eye of the needle 76.

The termination of the threading is accomplished by the rotation of the abutment carrier 62 which brings the abutment 61 into engagement with the switch contact 60. For this purpose it is requisite that the gearing ratio of worm 31 and pinion 63 be so selected that the carrier member describes one full revolution for the total of rotations through which the threading shaft 22 must pass in order to move the spiral from the

place ahead of eye 35 to a place shortly following eye 38. As soon as the contact 60 is actuated, the normally closed switch S2 will be opened and the circuit of the motor will be broken.

It should be manifest that the commencement and termination of the threading is entirely independent of the normal stitching operation. Since the starter switch S3 of the threading device cannot be started without at the same time disengaging the stitching mechanism and also, in the embodiment shown, the expansion mechanism, no danger exists that the stitching or expansion will interfere with the threading, and vice versa. If the machine is to be started after completion of the threading, the lever 53 must again be pushed inwards into the position shown in Figs. 3 and 4 and this will automatically disconnect the entire threading mechanism by sliding shaft 10 to the front and disengaging the gear 13 from gear 23.

It will be obvious that a number of modifications may be made in my device without departing from the spirit of the invention. For instance, a member other than an endless spiral could be employed to carry and guide the thread through the eyelets. Also, the usefulness of my device is not limited to a sewing machine or to the particular type of lock stitch machine illustrated in the drawings. It can be employed in any kind of textile or other machine where the problem arises to pass a thin thread through a plurality of narrow apertures.

I, therefore, do not wish to be limited otherwise than by the language of the appended claims.

What I claim is:

1. A device for guiding a thread through a plurality of eyelets, comprising an endless movable carrier member, said member passing through said eyelets and being adapted to carry with it a thread secured to it, and means to impart a lengthwise movement to said carrier member and thus to guide the thread through the eyelets.

2. A device for guiding a thread through a plurality of eyelets comprising an elongated carrier member, the said member extending permanently through said eyelets, and means to impart a movement to said member along a path leading through said eyelets whereby a thread secured to said member may be guided through said eyelets.

3. A device for guiding a thread through a plurality of eyelets, comprising an endless carrier member extending permanently through all of the said eyelets, a rotatable support for operative engagement with said carrier member, and drive means for rotating said support whereby a lengthwise movement is imparted to said member along a revolving path and a thread attached to it is guided through the said eyelets.

4. A device for guiding a thread through an eyelet, comprising an endless spiral, passing through said eyelet and adapted to carry with it a thread placed between its convolutions, and means to impart a lengthwise movement to the spiral and thus to guide the thread through said eyelet.

5. A device for guiding a thread through an eyelet, comprising a distensible endless spiral, passing through said eyelet and adapted to carry with it a thread placed between its convolutions, means to place tension upon said spiral and means to impart a lengthwise movement to the spiral and thus to guide the thread through said eyelet.

6. A device for guiding a thread through a plurality of eyelets, comprising a rotatable support, an endless member operatively engaged by said

support and passing through said eyelets, the endless member being adapted to carry with it a thread attached to it, and means for rotating said support, thereby imparting a lengthwise movement to the endless member and thus guiding the thread through the eyelets.

7. In a sewing machine of the type having cooperating stitching mechanisms in the base and top portion of the machine and individual drive shafts for said stitching mechanisms, a device for guiding the thread through an eyelet, comprising in combination, a rotary shaft extending parallel to said drive shafts, a sheave, an endless member passing through the said eyelet and adapted to carry with it a thread secured to it, mating gears associated with said sheave and said endless member, and means for selectively connecting the said rotary shaft of the threading mechanism and the said drive shafts of the stitching mechanism to a power source.

8. In a sewing machine of the type having cooperating stitching mechanisms in the base and top portion of the machine and individual drive shafts for said stitching mechanisms, a device for passing the thread through a plurality of eyelets disposed on the machine, comprising in combination, an endless member passing through the said eyelets and adapted to carry with it a thread attached to it, a support for said endless member, a mechanism for imparting a lengthwise movement to said endless member, an electric motor, means for selectively connecting the said mechanism for moving the said endless member and the said drive shafts of the stitching mechanisms with the transmission from the electric motor, a switch control for the motor, and a lever for actuating the switch, the lever having a linkage connection to said means for selective connection of the moving mechanism of said endless member and of the stitching mechanisms, whereby closing of the switch simultaneously connects the threading shaft and disconnects the stitching shafts.

9. In a sewing machine of the type having cooperating stitching mechanisms in the base and top portion of the machine and individual drive shafts for said stitching mechanisms, a device for passing the thread through a plurality of eyelets disposed on the machine, comprising in combination, a rotary shaft extending parallel to said drive shafts, a sheave, an endless member passing through the said eyelets and adapted to carry with it a thread attached to it, mating gears associated with said sheave and said rotary shaft for imparting a lengthwise movement to said endless member, an electric motor, means for alternatively connecting the said rotary shaft of the threading mechanism and the said drive shafts of the stitching mechanisms with the transmission from the electric motor, and switch means to break the circuit of the motor at the end of the threading operation.

10. In a sewing machine of the type having cooperating stitching mechanisms in the base and top portion of the machine and individual drive shafts for said stitching mechanisms, a device for passing the thread through an eyelet, comprising in combination, a rotary shaft extending parallel to said drive shafts, a sheave, an endless member passing through the said eyelet and adapted to carry with it a thread attached to it, mating gears associated with said sheave and said rotary shaft for imparting a lengthwise movement to said endless member, an electric motor, means for alternatively connecting the

said rotary shaft of the threading mechanism and the said drive shafts of the stitching mechanisms with the transmission from the motor, a switch for closing the circuit of said motor, a second switch for automatically breaking said circuit at the end of the threading operation, the latter switch being normally closed, an actuating member adapted to engage and thereby to open the second switch, a revolving carrier for the actuating member, a gear connection between the revolving carrier and the rotary shaft of the threading mechanism, the gearing ratio being so selected that the actuating member is brought into engagement with the second switch upon a predetermined degree of revolution of its carrier.

11. In a sewing machine of the type having cooperating stitching mechanisms in the base and top portion of the machine and individual drive shafts for said stitching mechanisms, a device for passing the thread through a plurality of eyelets disposed on the machine, comprising in combination, a rotary shaft extending parallel to said drive shafts, a sheave, an endless distensible member passing through the said eyelets and adapted to carry with it a thread attached to it, mating gears associated with said sheave and said rotary shaft for imparting a lengthwise movement to said endless member, an electric motor, means for alternatively connecting the said rotary shaft of the threading mechanism and the said drive shafts of the stitching mechanisms with the transmission from the motor, a switch for closing the circuit of said motor, a second switch for automatically breaking said circuit at the end of the threading operation, the latter switch being normally closed, an actuating member adapted to engage and thereby to open the second switch, a revolving carrier for the actuating member, a gear connection between the revolving carrier and the rotary shaft of the threading mechanism, the gearing ratio being so selected that the actuating member is brought into engagement with the second switch upon a predetermined degree of revolution of its carrier, the said circuit breaking switch being movably carried by the frame, and disposed normally without reach of the actuating member and adapted to be moved into engagement position at the beginning of the threading operation.

12. A device constructed in accordance with claim 11, said device including a tension member carried by the frame and having one of the eyelets secured to it, means connected to said tension member for moving the said circuit breaking switch and further means for moving the said

tension member so as to tension the said distensible member simultaneously with bringing the said circuit breaking switch into engagement position.

13. A device constructed in accordance with claim 11, including a tubular member carried by the frame, a shaft vertically slideable in the tubular member and having one of the eyelets secured to it, so as to put the distensible member under tension by sliding the shaft outwardly, a cam member attached to said slideable shaft and adapted to move the said circuit breaking switch into engagement position at the beginning of the threading operation, and means to raise the said slideable shaft and cam member.
14. A threading device including in combination a sewing machine, a needle bar forming a part of said machine, means providing a mounting for a body of thread at a point on said machine substantially remote from said needle bar, a plurality of thread-guiding elements to be engaged by a thread and movable means extending between said mounting and bar and in operative relationship to said guiding elements for passing the end 20 of a thread from said body to a point adjacent the end of the bar and with the intermediate portion of the thread disposed in operative contact with said elements.
15. A threading device, including in combination a sewing machine, a movable needle bar forming a part of said machine, a source of power, means normally connecting said source with said bar to move the latter, means providing a mounting for a body of thread at a point substantially remote from said needle bar, movable means extending between said mounting and bar for passing the end of a thread from said body to a point adjacent said bar, further connecting means for coupling said movable means with said 30 source of power to cause an operation of the former and means for rendering the connecting means between said source of power and needle bar inoperative to transmit power when said movable means is operated.
